(57) **CLAIM**

The ornamental design for a plasma generator, as shown and described.

DESCRIPTION

FIG. 1 is a front elevational view of the plasma generator according to one embodiment of the present invention; FIG. 2 is a rear elevational view of the plasma generator shown in FIG. 1;

FIG. 3 is a left-side elevational view of the plasma generator shown in FIG. 1;

FIG. 4 is a right-side elevational view of the plasma generator shown in FIG. 1;

FIG. 5 is a top plan view of the plasma generator shown in FIG. 1;

FIG. 6 is a bottom plan view of the plasma generator shown in FIG. 1;

FIG. 7 is a top, front, and right-side perspective view of the plasma generator shown in FIG. 1;

FIG. 8 is a bottom, front, and right-side perspective view of the plasma generator shown in FIG. 1;

FIG. 9 is a front elevational view of the plasma generator according to one embodiment of the present invention;

FIG. 10 is a rear elevational view of the plasma generator shown in FIG. 9;

FIG. 11 is a left-side elevational view of the plasma generator shown in FIG. 9;

FIG. 12 is a right-side elevational view of the plasma generator shown in FIG. 9;

FIG. 13 is a top plan view of the plasma generator shown in FIG. 9;

FIG. 14 is a bottom plan view of the plasma generator shown in FIG. 9;

FIG. 15 is a top, front, and right-side perspective view of the plasma generator shown in FIG. 9;

FIG. 16 is a top, rear, and right-side perspective view of the plasma generator shown in FIG. 9;

FIG. 17 is a front elevational view of the plasma generator according to one embodiment of the present invention;

FIG. 18 is a rear elevational view of the plasma generator shown in FIG. 17;

FIG. 19 is a left-side elevational view of the plasma generator shown in FIG. 17;

(Continued)

FIG. 20 is a right-side elevational view of the plasma generator shown in FIG. 17;
FIG. 21 is a top plan view of the plasma generator shown in FIG. 17;
FIG. 22 is a bottom plan view of the plasma generator shown in FIG. 17;
FIG. 23 is a top, front, and right-side perspective view of the plasma generator shown in FIG. 17; and,
FIG. 24 is a top, rear, and right-side perspective view of the plasma generator shown in FIG. 17.
The broken lines in the drawings depict portions of the article that form no part of the claimed design.
